Atkins.

UNITED STATES PATENT OFFICE.

HERMAN G. MARZYCK, OF JACKSONVILLE, FLORIDA.

METHOD OF AND APPARATUS FOR REMOVING THREADED MEMBERS.

1,380,071.

Specification of Letters Patent. Patented May 31, 1921.

Application filed July 29, 1920. Serial No. 399,950.

To all whom it may concern:

Be it known that I, HERMAN G. MARZYCK, a citizen of the United States, residing at 505 Main street, Jacksonville, in the county of Duval and State of Florida, have invented a new and useful Improvement in Methods of and Apparatus for Removing Threaded Members, of which the following is a specification.

10 This invention relates to the method of and apparatus for removing threaded members, and more particularly to the method of and apparatus for removing the broken end of a threaded pin that is left in a hole 15 where access to both ends of the piece may be had.

It frequently happens that a pin, bolt or other part which is held in place by having its end threaded into a hole, breaks off 20 leaving the threaded end in the hole. Before a new part can be put in place the broken end must be removed from the hole. This is frequently very difficult owing to the fact that the piece originally was screwed 25 in tightly and after being broken off does not leave enough projecting to furnish a grip for a pipe wrench or similar tool.

I have shown a device embodying the features of my invention in the accompanying 30 drawings in which Figure 1 is a vertical sectional view of my device in place on a broken end of a pedal pin in a crank. Fig. 2 is a view in perspective of a bit used in connection with the device. Fig. 3 is a view 35 in perspective of the arm of the device adapted to hold a bit. Fig. 4 is a view in perspective of another form of bit. Fig. 5 is a vertical sectional view of the device being used to remove the broken end of a pin 40 where such end has a slot or nick adapted to receive a screw driver blade.

As shown in said drawings, 7 indicates any part of any kind of device, for example, the end of a bicycle or motor-cycle crank. 45 The end of 7 is provided with a threaded hole 8 extending entirely therethrough for the purpose of retaining the threaded end of a bolt or pin such as a pedal pin. 9 indicates the threaded end of such bolt, pin or 50 other part which has been broken off in the hole 8.

My improved device comprises a screw clamp 10 having one of its jaws or arms 11 provided with a threaded hole 12 adapted to 55 accommodate the screw 13 which has its inner end pointed as indicated by 14, and its

outer end squared as indicated by 15 in order to permit turning by means of a wrench or similar tool. The other jaw or arm of the clamp indicated by 20 is provided with a 60 square hole 21 in which is adapted to fit the squared end 22 of a bit 23. The bit 23 has its other end serrated, or notched to form the radial edges 24.

In the use of the device, the clamp is put 65 in the position shown in Fig. 1, with the bit 23 in place in the clamp and its serrated end against one end of the broken part 9. The screw 13 is then screwed in until the pointed end 14 comes into contact with the 70 other end of the broken part 9. The screw 13 is then tightened until the teeth 24 bite into and engage firmly in the end of the broken part 9. When the clamp has thus been firmly fixed in place, the clamp itself 75 is rotated. This will cause rotation of the bit 23, and consequent rotation of the part 9. In most instances a slight rotation of the part 9 will loosen it sufficiently so that it can be removed by hand. If it does not become sufficiently loosened, however, by this slight rotation, it is obvious that the clamp 80 can be loosened, turned back a distance, again put in place, and again rotated. In this way, if necessary, the clamp can be 85 used until the part 9 is entirely out of the hole, or projecting sufficiently to afford engagement by a pipe wrench or similar tool.

In some instances the part broken off in the hole is provided at one end with a slot 90 or nick adapted to receive the blade of a screw driver. In Fig. 5 I have shown such a part as indicated by 9^a provided with the slot 31. Where such a slot is offered I provide a bit 32 for use with the clamp. The 95 bit 32 has a squared end 33 similar to the squared end 22 of the bit 23. Its other end has a screw driver blade 34 adapted to engage with the slot 31. In Fig. 5 the clamp is shown in place with the bit 32 having its 100 blade in engagement with the slot. The device is used in the same way as explained before, except that it does not need to be fastened so tight since the blade 34 engaging with the slot in the part 9^a will cause 105 rotation and loosening of the part when the clamp is rotated.

What I claim as new and desire to secure by Letters Patent is:

1. In combination with a clamp having 110 aligned openings for bits, a threaded bit working in one of said openings, and a bit

non-rotatably fitting the other of said openings to coöperate with said threaded bit to clamp a part between the bits, said threaded bit having its inner end pointed and the 5 other bit being provided with a surface to prevent rotation of the part clamped with respect to said bit.

2. In a device of the character set forth, a clamp having one of its jaws provided 10 with a threaded hole, a screw extending through the threaded hole and having its inner end pointed, and a bit non-rotatably mounted in the other jaw of the clamp, said bit lying in alinement with the screw and 15 provided with a surface to prevent rotation with respect to said bit of a part clamped between said bit and the screw.

3. In a device of the character set forth, a clamp having one of its jaws provided 20 with a threaded hole, a screw extending through the threaded hole and having its inner end pointed, and a bit non-rotatably mounted in the other jaw of the clamp, said

bit lying in alinement with and extending inwardly toward the point of the screw and 25 provided with a surface to prevent rotation with respect to said bit of a part clamped between the bit and the pointed inner end of the screw.

4. In a device of the character set forth, 30 a clamp having one of its jaws provided with a threaded hole, a screw extending through the threaded hole, and a bit non-rotatably mounted in the other jaw of the clamp, said bit and screw lying in alinement with each other and adapted to co-operate to clamp a part between them, the bit being provided with a surface to prevent rotation of the part clamped with respect to said bit, and the screw being so constructed as to permit rotation thereof with respect to the part clamped. 40

In testimony whereof, I have hereunto set my hand, this 24 day of July 1920.

HERMAN G. MARZYCK.
